UNITED STATES PATENT OFFICE.

JOHN F. RATHBONE, OF ALBANY, NEW YORK.

DESIGN FOR A STOVE.

Specification forming part of Design No. 142, dated August 7, 1847.

To all whom it may concern:

Be it known that I, JOHN F. RATHBONE, of Albany, in the county of Albany and State of New York, have invented or produced a new ornamental Design for a Cooking-Stove; and I do hereby declare that the accompanying drawings are full and accurate representations of my said design.

Figure 1 is a perspective view; Fig. 2, a view of the front, with summer arrangement attached, upon a large scale to show the detail of ornament; Fig. 3, a side plate, and Fig. 4 a rear view of the stove.

The ornamental figures, &c., though not easily described in words, are fully represented in the drawings.

What I claim as my invention, and desire to secure by Letters Patent, is—

The combination and arrangement of ornamental figures, &c., exhibited in the accompanying drawings, forming an ornamental design for a cooking-stove.

JOHN F. RATHBONE.
